APPARATUS FOR FLANGING OPENINGS IN
TUBE TYPE HEADERS

John G. Zummach, Racine, Wis., assignor to
Young Radiator Company, Racine, Wis., a
company of Wisconsin

Application May 3, 1943, Serial No. 485,548

4 Claims. (Cl. 153—25)

It is difficult to flange openings outwardly in tubes, especially when the tubes are long and have a number of closely spaced openings therein to be flanged.

The present invention relates to convenient means for flanging any number of closely spaced holes in tubes of any length.

An object of the present invention is to uniformly flange the openings in tubes in groups in a simple and economical manner.

To these and other useful ends, my invention consists of parts, combinations of parts, or their equivalents, and mode of operation, as herein-after described and claimed and shown in the accompanying drawings in which:

Fig. 1 is a partially sectioned end view of my device, the section being taken through one of the openings before being flanged.

Fig. 2 is a partially sectioned front view of my device, the section being taken through one of the openings before being flanged.

Fig. 3 is a view similar to Figure 1 partially sectioned through a flanged opening.

Fig. 4 is a fractional view of my device sectioned on line 4—4 of Figure 2 with the flanging device removed.

Fig. 5 is an enlarged detail illustrating the tube positioning device.

Fig. 6 is a view similar to Figure 5 taken through a flanged opening.

As thus illustrated, the device comprises a base plate 10 adapted to be attached to a punch press base to which a support base 11 is rigidly attached, having preferably a trench 12 adapted to embrace the lower half of tube 13. Tube 13 is first provided with one or more spaced holes 14. Two holding blocks 15 and 16 are slidably held on support base 11 by means of straps 18—18 and cap screws 19.

Blocks 15 and 16 are curved at their inner lower corners as at 20—20. These curves may embrace tube 13 as follows:

Blocks 15 and 16 are cut-away as at 22 forming circular openings which align with holes 14 in tube 13 when the blocks are gripping the tube.

In the figures, I have shown my device as adapted to flange three tube holes simultaneously; therefore in this design there will be three pairs of cut-away portions 22 in blocks 15 and 16, these blocks each having rectangular apertures 25 which are on their inner upper corners cut-away as at 26. Blocks 15 and 16 each have apertures 27—27 into which I place balls 28—28 and springs 29—29 (one each not shown) each aperture 27 having a screw plug 30 so pressure is

added on balls 28 for a purpose which will hereinafter appear.

A head 35 having a holding shank 36 is adapted to be attached to the punch press head. Rectangular bars 37—37 are suitably secured to head 35 as at 38. These bars are adapted to slidably fit into openings 25 and are shaped as shown in Figure 3, having a narrowed end 39 formed by angles 40 which are adapted to contact surfaces 5 26 when head 35 moves downwardly so as to overcome springs 29 and move blocks 15 and 16 inwardly to the position shown in Figure 1 so as to grip tube 13. Blocks 15 and 16 are adapted to be moved outwardly by pressure of springs 15 29 when members 37 are raised to the position shown in Figure 3; thus to move far enough away from tube 13 to clear the flanges formed in the tubes as will hereinafter appear and so the tube 20 14 to be flanged.

I provide preferably three shanks 50 which are secured to member 35 in line with the three openings formed by cut-away portions 22 and with the three holes 14 in tube 13. Members 50 are 25 split as at 51 and normally assume the shape shown in Figure 1 and having near their lower ends cone shaped projections 52—52 and shank extensions 53—53 with projections 54 at their lower ends adapted to be pressed into sleeves 55, 30 projections 54 being tapered as at 56 so they will readily enter the sleeves.

Before this operation, sleeves 55 are previously placed in openings 57 in a shaft 58 which is about the length of tube 13, these openings being arranged so there is one in line with each opening 14 (see Figure 5). The tube and shaft are held together and in alignment with members 50 by means of a bracket 60 secured preferably to one of members 18 (not shown) and positioned so keeper 61 may be inserted into aperture 62 and through hole 14 and into sleeve 55, member 60 being positioned so holes 14 will be in alignment with members 50.

The holding device shown in Figure 5 is suitable for holding the tube in position before the holes in the tube are flanged. I provide means for holding the tubes into position after being flanged as illustrated in Figure 6.

Members 57 are preferably provided with ledges 50 63 on which sleeves 55 rest; thus when head 35 is moved downwardly, projections 54 will contact the sleeve and move together to the position shown in Figure 3 and after passing through the sleeve, projections 54 will move to the position shown in Figure 2.

Sleeve 55 is suitably tapered at its upper end so when head 35 moves upwardly, this sleeve will form flanges 64. When head 35 is raised to its upper position, projections 52 will enter tapered openings 65 in bracket 66 far enough to release sleeves 55 as shown in Figure 3; thus tube 13 may be moved for the next operation and member 61 inserted to hold the tube and shaft in position for the next operation.

It will be seen that there will come a time when a flanged opening must be used for locking the tube and shaft into position. In this event, a keeper 67 may be inserted into opening 62 so the flanged opening and opening 51 are engaged.

Clearly many minor detail changes may be made without departing from the spirit and scope of the present invention, as recited in the appended claims.

Having thus shown and described my invention, I claim:

1. A tube opening flanging device of the class described, comprising a stationary base plate and an oscillating head, said base plate having blocks slidably mounted thereon with means on their inner surfaces for gripping the tube when moved together, adjacent cut-away portions in said blocks adapted to form circular openings somewhat larger than the holes in the tube to be flanged, a shaft in the tube and openings in the shaft somewhat larger than the holes in the tube, sleeves in said shaft openings, a number of plungers secured to said head, the lower ends adapted to move through said circular openings and the holes in the tube and said sleeves and having means to lock the plungers to the sleeves when in their lowest positions whereby when the oscillating head is moved upwardly, the sleeves will be caused to form flanges around the holes and within the openings formed in said blocks, manually operated anchoring means adapted to

hold certain sleeves and holes in the tube in alignment with the adjacent circular openings.

2. A device as recited in claim 1 including; means associated with said blocks and head adapted to cause the blocks to firmly engage the tube when the head is in its lowest position and to move the blocks away from the tube when the head is moved to its highest position.

3. A device as recited in claim 1 including; means whereby when said plungers are in their highest position, the sleeves will be released automatically.

4. A tube opening flanging device of the class described, comprising a stationary base plate and an oscillating head, said base plate having blocks slidably mounted thereon with means on their inner surfaces for gripping the tube when moved together, adjacent cut-away portions in said blocks adapted to form a circular opening somewhat larger than the hole in the tube to be flanged when the blocks are gripping the tube, a shaft in the tube and an opening in the shaft somewhat larger than the hole in the tube, a sleeve in said shaft opening, a plunger secured to said head, the lower end adapted to move through said circular opening and the hole in the tube and said sleeve and having means to lock the plunger to the sleeve when in its lowest position, whereby when the oscillating head is moved upwardly, the sleeve will be caused to form a flange around the hole and within the opening formed in said blocks, means adapted to hold the hole in the tube and the opening in the shaft in alignment with said plunger, means associated with said blocks and head adapted to cause the blocks to firmly engage the tube when the head is in its lowest position and to move the blocks away from the tube when the plunger is moved to its highest position.
